HOLDER FOR USE IN SHARPENING GUN DRILLS

Marvin W. Mitzelfeld and Allan R. Poulin, Rochester,
Mich., assignors to National Twist Drill & Tool Com-
pany, Rochester, Mich., a corporation of Michigan

Filed Mar. 9, 1959, Ser. No. 54,905

Term of patent 14 years

(Cl. D54—13)

FIG.2.

FIG.1.

FIG.3.

FIG.4.

FIG.5.

Figure 1 is a top plan view of a holder for use in sharpening gun drills embodying our new design;

Figure 2 is an elevational view taken from the bottom of Figure 1;

Figure 3 is an elevational view taken from the right of Figure 1;

Figures 4 and 5 are perspective views thereof as seen from the left and right respectively of Figure 1.

The dominant features of our design reside in the portions shown in full lines.

We claim:

The ornamental design for holder for use in sharpening gun drills, substantially as shown and described.
